(57) **CLAIM**

We claim the ornamental design for an oscillating tool blade, as shown and described.

DESCRIPTION

FIG. 1 is a top perspective view of an oscillating tool blade showing my new design;

FIG. 3 is a rear elevation view thereof;

FIG. 2 is a front elevation view thereof;

FIG. 4 is a right side elevation view thereof;

FIG. 5 is a left side elevation view thereof;

FIG. 6 is a top plan view thereof; and,

FIG. 7 is a bottom plan view thereof.

The dash-dash broken lines shown in FIGS. 1-7 illustrate portions of the oscillating tool blade that form no part of the claimed design; The dot-dash broken lines shown in FIGS. 1-7 define the bounds of the claimed design and form no part thereof.

1 Claim, 5 Drawing Sheets(56)
